UNITED STATES PATENT OFFICE.

FRANK ROBINSON, OF CHICAGO, ILLINOIS.

SPARK-PLUG.

1,303,965.

Specification of Letters Patent. Patented May 20, 1919.

Application filed July 15, 1916. Serial No. 109,469.

To all whom it may concern:

Be it known that I, FRANK ROBINSON, a citizen of the United States, and a resident of the city of Chicago, in the county of Cook and State of Illinois, have invented 5 certain new and useful Improvements in Spark-Plugs; and I do hereby declare that the following is a full, clear, and exact description of the same reference being had 10 to the accompanying drawings, and to the numerals of reference marked thereon, which form a part of this specification.

This invention relates to an improved type of spark plug in which the parts are so arranged and constructed that the plug is 15 practically self cleaning, and furthermore permits a ready removal of the parts liable to become fouled or damaged without necessitating complete detachment of the entire 20 plug from the engine cylinder in which it is connected.

It is an object of this invention to construct a spark plug for internal combustion engines constructed to keep its terminals 25 clean from fouling materials.

It is also an object of this invention to construct a spark plug consisting of a tubular insulating core having a combustion chamber therein into which projects a feed 30 wire on which a baffle plate is mounted to prevent the terminal of said feed wire from becoming fouled.

It is a further object of this invention to construct a spark plug consisting of an apertured sleeve for receiving a chambered insulating core removably held in place by means 35 of a gland threaded into said sleeve, said sleeve provided with a conductor projecting into the chambered core and having a baffle 40 plate near the terminal end thereof to prevent fouling materials from entering said chamber thus keeping the terminal clean.

It is furthermore an important object of 45 this invention to provide a spark plug comprising a chambered tubular insulating core having a priming tube therein for connecting a priming cup and a feed wire with said chamber, said core being removably mounted in a sleeve having a second feed wire projecting upwardly therein into said chamber to a point opposite the terminal end of said priming tube and having means mounted 50 near the terminal end thereof to prevent fouling of the ignition terminals.

It is finally an object of this invention to 55 construct an improved spark plug consist-

ing of few parts readily taken apart for repairs without necessitating entire detachment of the plug from the engine cylinder, and provided with a means for preventing 60 fouling of the ignition terminals of the plug.

The invention (in a preferred form) is illustrated in the drawings and hereinafter more fully described.

In the drawings:

Fig. 1, is a side elevational view of a spark plug embodying the principles of my invention.

Fig. 2, is a central vertical section taken through the spark plug with parts shown in 70 elevation.

Fig. 3, is a top plan view of the spark plug.

Fig. 4, is a section taken on line 4—4, of Fig. 2.

Fig. 5, is a section taken on line 5—5, of Fig. 2.

Fig. 6, is a section taken on line 6—6, of Fig. 2.

Fig. 7, is a central vertical section of the 80 upper end of a modified form of spark plug.

As shown in the drawings:

The upper end of an internal combustion engine cylinder or a removable plug therein, is indicated by the reference numeral 1, and 85 threaded into a suitable aperture therein, and provided with a copper asbestos gasket 2, is a sleeve comprising an externally threaded plug 3, having integrally formed thereon a hexagonal portion 4, affording a 90 nut to receive a wrench engaged therewith to tighten said sleeve in sealing relation with the cylinder 1. Integrally formed on said hexagonal portion 4, is a cylindrical shell or casing 5, internally threaded at its upper 95 end, and provided in its side walls with a plurality of small ventilating or cooling apertures 6.

Fitting within said shell 5, and bearing upon a suitable packing 7, is a relatively 100 long tubular core 8, of porcelain or other suitable insulating material having an enlarged portion 9, at the lower end thereof which fits snugly against the inner walls of said shell 5. Said enlarged portion 9, has 105 formed therein a combustion chamber 10, which communicate with a passage 11, axially formed through said plug 3 and with said hexagonal portion 4. An axial passage 110 communicating with the upper end of said chamber 10, is also formed in said core 8, and projecting therethrough is a priming

tube 12, the lower end of which projects into said combustion chamber and has integrally formed thereon a flange 13, adapted to contact the walls of said chamber to prevent the tube from being drawn through said core and further affording a suitable anchor or catch to permit said tube to be locked in sealing relation with the core by the lock nuts 14, engaged on the upper threaded end of said tube which projects beyond the upper end of the core 8, as clearly shown in Fig. 2. Threaded on the upper end of said tube 12, and communicating with the interior thereof is a priming cup 15, provided with an insulated handle 16, and with a binding post 17, for attaching an ignition wire or conductor 18, to the plug.

To removably hold said core 8, in position 20 within said shell 5, a threaded gland or lock nut 19, is threaded into the upper end of the shell 5, and presses against a packing gasket 20, resting on the upper end of the enlarged portion 9, of the core to clamp the same in 25 place sealed and properly aligned within the sleeve.

Secured to the plug 3, and projecting inwardly and upwardly through the center of the passage 11, and into the combustion chamber 10, is a second feed wire or conductor 21, flanged outwardly near its upper end to hold in position a downwardly curved baffle plate 22, of a diameter equal to the diameter of the passage 11. Said baffle plate 35 22, is held in position against said flanged portion of the conductor 21, by a metallic cap or nut 23, threaded on the upper end of said conductor, directly below the lower end of the tube 12, forming ignition terminals 40 for the spark plug. The baffle plate 22, prevents oil or other fouling elements resulting from cylinder explosions from passing upwardly through the passage 11, into the upper end of the combustion chamber 10, to 45 thus foul the ignition terminals of the spark plug. To prevent the enlarged portion 9, of the core 8, from becoming too hot the apertures 6, are provided, as already described, to ventilate and permit cooling of said core. 50 In the modified form of spark plug shown in Fig. 7, the construction of the device is identical with that already described, except that the priming mechanism is omitted and replaced by a cap 24, threaded on the 55 upper end of the tube 12, clamping a conductor 25, in position against the lock nuts 14. Priming in this case is performed by removing the cap 24, and supplying the priming liquid through the tube 12. 60 From the construction of the spark plug it will of course be seen that the various parts may be removed or replaced without necessitating the removal of the entire plug from the engine to which it is attached. I 65 am also aware that various details of the

construction may be varied through a wide range without departing from the principles of this invention, and I therefore do not purpose limiting the patent granted otherwise than necessitated by the prior art.

I claim as my invention:

1. In a spark plug of the class described, a sleeve member adapted to be threaded into the wall of the combustion chamber of an engine, an insulating core removably mounted therein, said insulating core having a combustion chamber therein larger than the passage in the sleeve, a spark terminal projecting into said enlarged chamber, a second spark terminal in said sleeve projecting upwardly into said enlarged chamber to a point below said first mentioned terminal, and means mounted thereon to keep said terminals clean.

2. In a spark plug of the class described, a sleeve adapted to be threaded into the combustion chamber of an internal combustion engine, said sleeve having a plurality of ventilating apertures and a passage therein, an insulating core in said sleeve, a gland 90 threaded into said sleeve for holding said core in position, said core having a combustion chamber and an axial passage therein communicating with one another, said combustion chamber registering with the passage in said sleeve, a priming tube in said core passage projecting into said combustion chamber to afford a terminal, priming means connected on the upper end of said tube, a feed wire connected thereto, a second feed wire connected to said sleeve and projecting upwardly through said sleeve passage into said combustion chamber to afford a second terminal, with baffle means removably mounted on said second terminal within said combustion chamber to deflect fouling materials resulting from explosions from entering the combustion chamber to foul said terminals.

3. In a device of the class described, an apertured sleeve having a passage therein, a passaged insulating core therein, an enlarged portion integrally formed on said core having a combustion chamber therein, priming means removably mounted on said core and 11 projecting into said combustion chamber to afford a terminal, mechanism connected with said sleeve and projecting through the passage therein into said combustion chamber to afford a second terminal, and means threaded into said sleeve to contact said enlarged core portion to sealingly hold said core in position, said mechanism adapted to keep said terminals clean.

4. A spark plug comprising a sleeve, an insulating member secured thereto having a chamber therein larger than the bore of said sleeve, conductors projecting into said enlarged chamber, and a baffle plate in said chamber on one of said conductors below the 130

F. ROBINSON.

SPARK PLUG.
